To all whom it may concern:

Be it known that I, Jacob Wagner, a citizen of the United States, residing in Chicago, in the county of Cook and State of Illinois, have invented a new, original, and ornamental Design for a Combined Folder for Bills, Pictures, Cards, or the like, of which the following is a specification, reference being had to the accompanying drawing, forming part thereof.

Fig. 1 is a front elevational view of a combined folder for bills, pictures, cards, or the like in opened position, with the picture holding member portion in unfolded position, showing my design.

Fig. 2 is another front elevational view of the folder shown in Fig. 1 with the picture holding member portion thereof in folded position, and

Fig. 3 is an edge view of the folder shown in Figs. 1 and 2, in closed position.

The dominant features of my design reside in the portions shown on the drawing in full lines.

I claim:
